UNITED STATES PATENT OFFICE.

ROBERT MCK. THOMAS, OF NEW YORK, N. Y., ASSIGNOR TO THOMAS & BETTS, OF SAME PLACE.

DESIGN FOR A COUPLING OR NIPPLE FOR PIPES.

SPECIFICATION forming part of Design No. 33,957, dated January 22, 1901.

Application filed December 24, 1900. Serial No. 40,980. Term of patent 14 years.

To all whom it may concern:

Be it known that I, ROBERT MCK. THOMAS, residing at New York, in the county and State of New York, have invented and produced a new and original Design for a Coupling or Nipple for Pipes, of which the following is a specification.

The drawings show, in Figure 1, in side elevation, a coupling or nipple for pipes in which my novel design is embodied. Fig. 2 is a vertical transverse section of the same on the line $x-x$, Fig. 3; and Fig. 3, a plan view.

In the drawings illustrating my coupling or nipple of novel configuration, a designates the body or shank portion of cylindrical contour terminated at one end by a head b of octagonal form exteriorly and presenting inwardly a shoulder c , which surrounds a cir-

cular aperture and is curved on both sides of a plane transverse the axis of the nipple. 20 The bore of the nipple at the shoulder is of less diameter than at the region d , and adjacent the shoulder, between it and the portion d , appears a groove e .

Having thus described my design, what I 25 claim, and desire to secure by Letters Patent, is—

The design for a coupling or nipple for pipes, substantially as herein shown and described.

In testimony whereof I have signed my 30 name to this specification in the presence of two subscribing witnesses.

ROBERT MCK. THOMAS.
